[57] CLAIM

The ornamental design for a man-portable belt-mounted thermography system, as shown and described.

DESCRIPTION

FIG. 1 is a front perspective view of the man-portable belt-mounted thermography system with its environment, a man, shown in phantom;

FIG. 2 is a right side view of the system;

FIG. 3 is a left side view of the system;

FIG. 4 is a rear view of the system;

FIG. 5 is an angled front perspective view showing the system in a different configuration; and,

FIG. 6 is a left perspective view showing the system in a different configuration.
